COMBINED ADHESIVE MAGNETIC-ELECTRIC TAPE, RULER AND ACOUSTIC COUPLING

St. Barth Alaska, 3811 S. Scoville Ave.,
Berwyn, Ill. 60402

Filed Oct. 22, 1970, Ser. No. 26,728

Term of patent 14 years

Int. Cl. D14—03

U.S. Cl. D26—14

FIG. 1

FIG. 3

FIG. 2

FIG. 3

FIG. 4

FIG. 1 is a perspective view of a combined adhesive magnetic-electric tape ruler and acoustic coupling showing my new design;

FIG. 2 is a side elevation of the coupling and tape partially shown in section along line 2—2 of FIG. 1;

FIG. 3 is a cross-section of a modified embodiment of the magnetic-electric tape illustrated in FIG. 1; and

FIG. 4 is a cross-section of still a further modified embodiment of the magnetic-electric tape illustrated in FIG. 1;

The broken lines are shown for illustrative purposes only.

I claim:

An ornamental design for a combined adhesive magnetic-electric tape, ruler and acoustic coupling, as shown and described.
